UNITED STATES PATENT OFFICE.

SAMUEL K. POWELL, OF LOS ANGELES, CALIFORNIA.

BALL-CARRIER AND GAME-REGISTER.

1,011,486.

Specification of Letters Patent. Patented Dec. 12, 1911.

Application filed April 25, 1911. Serial No. 623,816.

To all whom it may concern:

Be it known that I, SAMUEL K. POWELL, a citizen of the United States, residing at Los Angeles, in the county of Los Angeles 5 and State of California, have invented a certain new and useful Ball-Carrier and Game-Register, of which the following is a specification.

My invention relates to a registering device for pool games and has for its object primarily to prevent the removal of the triangle, and the balls within the same, from the carrier without indicating such removal on the register.

With this and other objects in view, this invention consists of the features, details of construction, and combination of parts described in connection with the accompanying drawings, and then more particularly 20 pointed out in the claims.

In the drawings—Figure 1 is a plan view showing the carrier and the locking and registering mechanism for the triangle. Fig. 2 is a fragmentary plan view showing 25 the enlarging glass through which the registration on the indicator may be read. Fig. 3 is a front elevation of the device showing the cut away portion in the bottom of the carrier. Fig. 4 is a side elevation showing 30 the locking and register operating mechanism, and the bell. The front side of the support for the mechanism has been omitted. Fig. 5 is a sectional detail on lines X⁵ X⁵ of Fig. 4, showing the lock, and the mechanism for controlling the lock, and Fig. 6 is a fragmentary detail of the tongue and the lip for operating the bell.

The invention comprises a support of triangular shape, having a bottom 1, and side 40 walls 2 and 3, such support forming a carrier for a triangle 4 and the balls 5 used in the game. Said support is provided with a boxing 6, in which is housed a frame, consisting of two spaced plates 7 and 8, such 45 frame being fastened to one wall of the boxing by bolts 9. A latch bolt 10 extends through an opening in the plate 7 and one side of the boxing, and is arranged to engage a latch chamber 11 provided in one side 50 of the triangle 4. Said latch bolt 10 is held projected in the latch chamber 11 by a spring 12 coiled about the shank 13 thereof, which is normally housed in a boss 14' on plate 8 of the frame. Said latch bolt 10 is 55 rabbed to receive the peripheral edge of a cam disk 14, by means of which the latch

bolt is controlled. Said cam disk is mounted on a shaft 15, on to which it is fastened by a set screw 16 extending through a hub 17 integral with said disk. A bell 18 is 60 fastened on said hub 17, by screws 19. Mounted on said shaft 15, is the hub 20 of a finger 21, to the end of which is pivotally fastened a tongue 22. This tongue is held normally in contact with the upper face 65 of said finger 21 by a spring 23, such tongue being movable relatively to said finger when moved in one direction, as will appear more fully hereinafter. The shaft 15, on which the cam disk 14, bell 18 and finger 21 are 70 mounted, is normally under the tension of a spring 24, one end of which is fastened to the hub 20 of the finger 21, while its outer end is fastened in the plate 8 of the frame. In this manner the cam disk is held normally 75 in the position illustrated in Fig. 4, the cam portion of the disk being out of engagement with the rabbet of the latch bolt 10, which is in engagement with the latch chamber 11 of the triangle.

A stop 25 provided on the cam disk periphery, and alternately engaging the lugs 26 and 27 on the plate 7 of the frame, prevents greater rotation of the disk than the two lugs will admit of. The oscillation of the shaft 15, 80 by a key fitting the squared end 28 of the shaft, causes the cam disk 14 to be moved away from the lug 26, and the cam face engaging the rabbet of the latch bolt withdraws the bolt from the latch chamber 11 85 of the triangle. Such movement of the cam disk, as is obvious, occurs against the tension of the spring 24, and immediately upon the release of the key, the shaft and its complementary parts are forced to normal 90 position, leaving the latch bolt projected through the openings in the plate 7 and wall of the boxing.

On an arbor 29, fastened on the plate 8 of the frame, is a sleeve 30, provided with 100 a leaf spring 31, on to the end of which is fastened a hammer or knob 32, which is in direct alinement with the aforementioned bell 18. Said sleeve 30 is also provided with a pin 33, which is held in engagement with 105 a stud 34 by a spring 35. Said pin 33 is in the direct path of travel of the tongue 22 fastened on to end of the finger 21. Consequently when the shaft is oscillated by means of the key, the tongue 22 engages the pin 110 33, raising it away from the stud 34. The continued movement of the shaft causes the

tongue to slip engagement with said pin 33, which thereupon suddenly returns to normal position, causing the leaf spring 31 to yield to the shock and the hammer carried by the 5 end thereof to strike the bell 18. When the key is released, and the finger 21 returns to normal position, the tongue 22 striking against the pin 33 is raised relatively to the finger 21, and thereby glides past said pin 10 to original position.

On the cam disk 14 is pivoted a pawl 36, held normally against a stop pin 37, by a spring 38. Said pawl is arranged to engage a ratchet 39 when the cam disk 14 is oscillated, such ratchet serving to govern the registration on the register 40. The operation of the ratchet 39 occurs slightly in advance of the withdrawal of the latch bolt 10, thus absolutely preventing the removal 15 of the triangle 4 from the support before the register has been actuated. On the return movement of the cam disk 14 to normal position the pawl 36 glides over the ratchet 39, which is held stationary against 20 movement in the reverse direction by a dog 41, pivotally mounted on the plate 7 of the pawl, and held in contact with said ratchet by a spring 42.

As seen in Fig. 1, the bottom 1 of the support, is provided, centrally of the outside edge thereof, with an opening 43 of a size slightly smaller than the diameter of one of the balls. When the front wall of the triangle is parallel with the edge of the bottom 1, the opening 43 is too small to permit passage therethrough of one of the balls. When the wall of the triangle is in such parallel position, the latch bolt 10 is in engagement with the latch chamber 11 of the 35 triangle, and removal of the latter with the balls is impossible until the lock has been withdrawn, which action causes the register to be operated. Unless such wall of the triangle is in parallel alignment with the edge 40 of the bottom 1, the balls will drop through the opening, consequently dishonesty in registering the number of games played is guarded against.

The support is provided with a handle A 50 by which it is carried. The triangle used to "bunch" the balls, is inserted in the triangular support, as shown in Fig. 1, the lock 10 engaging the latch chamber 11, to hold the same in place and against removal. 55 When the triangle is thus locked, the support is taken to the rack, in which the balls have been placed by the players, and the balls deposited in the triangle. Before the triangle can be removed from the carrier or 60 support, the lock must be withdrawn from

the latch chamber, such withdrawal of the lock causing the register to be operated, as described. Since the triangle is necessary to "bunch" the balls, and in this device, the carrier cannot be used without the triangle 65 in place, it is obvious that each use of the triangle will be indicated on the register.

What I claim is—

1. A device comprising a triangular carrier for a plurality of balls, a triangle fitting 70 in said carrier to prevent the balls from falling out, means to lock said triangle in said carrier, means to control said lock to release said triangle from said carrier, and means to register the number of times said triangle is 75 removed from said carrier.

2. A device comprising a triangular carrier for a plurality of balls, a triangle arranged to fit in said carrier, said triangle having in one side thereof a latch chamber, 80 a lock engaging said latch chamber to lock said triangle in said carrier, means to control said lock to release said triangle from said carrier, and a mechanism coöperating with and controllable by said lock control- 85 ling means to register the number of times said triangle has been removed from said carrier.

3. A device comprising a triangular ball carrier having a cut-out portion of a size 90 sufficient for the passage of a ball therethrough, a triangle arranged to fit in and be carried with the balls by said carrier, said triangle being provided in one side thereof with a latch chamber, a bolt engaging said 95 latch chamber to lock said triangle in said carrier, one side of said triangle serving to constrict the cut-out portion in said carrier when locked therein, to prevent the passage of a ball therethrough, a means to operate 100 said bolt to withdraw same from the latch chamber of said triangle, and a registering mechanism coöperating with and controllable by said operating means.

4. A device comprising a support for a 105 plurality of balls, said support having a cut-away portion, a triangle fitting in said support, and arranged to close one side of said cut-away portion to prevent the ball 110 therein from falling out, a means to lock said triangle in said support, means to control said lock, and means to register the number of times said lock has been operated.

In testimony whereof I affix my signature in the presence of two witnesses.

SAMUEL K. POWELL.
